UNITED STATES PATENT OFFICE.

SELINA HAMBURGER, OF PITTSBURGH, PENNSYLVANIA.

DISPLAY STAND.

Application filed November 26, 1924. Serial No. 752,410.

This invention relates to display stands and has for an object to provide an improved construction wherein the parts may be quickly and easily adjusted to different positions.

Another object of the invention is to provide a display stand which may not only be adjusted to different positions but which may receive different supporting attachments whereby the stand may be used to display or support one or a large number of different objects.

A further object of the invention is to provide a display stand in which the standard may be quickly raised and lowered at any time, the structure being such that the standard is adapted to receive one or many supporting brackets, platforms and the like in different planes and in line with each other or at an angle to each other.

A still further object of the invention is to provide an improved construction over my co-pending application, Serial No. 563,342, of which this is in part a division.

In the accompanying drawings—

Figure 1 is a perspective view of a stand disclosing one embodiment of the invention.

Figure 2 is a fragmentary sectional view through Figure 1, approximately on line 2—2.

Figure 3 is a fragmentary enlarged vertical sectional view through part of the structure shown in Figure 1, the same illustrating the action of the catch and the way the brackets may be mounted.

Figure 4 is a sectional view through Figure 3, approximately on line 4—4.

Figure 5 is a fragmentary sectional view through Figure 3, approximately on line 5—5.

Figure 6 is a fragmentary side view of part of the standard shown in Figure 1 with a modified construction of base.

Figure 7 is a fragmentary side view of a modified form of standard to that shown in Figure 1.

Figure 8 is a view somewhat similar to Figure 3 but showing the standard illustrated in Figure 7 and a slightly modified form of catch for supporting the standard.

Figure 9 is a view in perspective of a shelf showing the bracket connection applied.

Referring to the accompanying drawing by numerals, 1 indicates a base which may be of any desired shape and any desired size,

said base having a threaded socket 2 for receiving the lower threaded end of the tube 3 which forms a socket for the standard 4 and in fact, acts in a certain sense as a part 60 of the standard structure of the stand. The standard 4 is made of a size to easily slide in the tube 3 but without any appreciable wobbling as indicated particularly in Figure 3.

From Figures 1 and 3 it will be noted that the standard 4 is provided with a number of cylindrical sections 5 merging into tapering sections 6 whereby annular shoulders 7 are provided. In each of the tubular sections 5 are passage-ways or apertures 8 and 9 extending entirely through the standard at right angles to each other. The standard 4 is hollow though it could be made solid without departing from the spirit of the invention. Co-acting with the shoulders 7 is a catch 10, said catch being provided with a pair of arms 11 and 12, said arms having journal extensions 13 and 14 extending into the tube 3 whereby the arms are 80 pivotally mounted. The arms merge into a handle 15 which is provided with a catch extension 16 adapted to extend through a suitable aperture 17 in tube 3 as indicated in Figure 3 whereby the catch extension may fit properly under one of the shoulders 7 and support the standard 4. The weight of the handle 15 and associated parts continually acts to hold the catch extension 16 in an inner position and ready to engage any of the shoulders 17 whenever permitted. However, whenever the standard 4 is raised vertically, the entire catch 10 will move to one side as indicated in dotted lines in Figure 3 until the catch extension 16 drops beneath 95 some particular shoulder 7. The top of the standard 4 is preferably threaded so that a suitable support or fitting 18 may be screwed thereon.

In order to provide shelves or other desired fittings 19, 20 and 21, the various apertures or passageways 8 and 9 have been provided so as to receive the ends of the various pins 22 connected to each of these members as indicated particularly in Figure 3. The pin 22 may be riveted or otherwise rigidly secured in position and projects beyond the body of the shelf or other fixture so as to be inserted into one of the apertures 8 or 9 an appreciable distance before the brace and catch 23 engages the tapering section 6. It will be noted that the parts are con-

structed to be readily applied or removed by a horizontal movement but sufficiently tight to prevent loose motion in respect to the pin 22 or loose motion in respect to the upper 5 end of the brace and catch 23 which slidingly engages the shoulder 7. When a weight is applied to the fixture any tendency to cause the same to swing downwardly is resisted both by the pin 22 and by the 10 brace and catch 23 engaging the shoulder 7. Under some circumstances a web 24 as shown in Figure 1 is provided so as to more firmly brace the fixture. This structure is 15 preferably used where the fixture is provided with a round bar as indicated by fixture 21. The outer end of fixture 21 may be threaded or otherwise formed to receive any suitable supporting plate or attachment 25.

20 In regard to the fixtures 19 and 20, the brace and catch 23 is preferably a substantially semi-circle in cross section and thereby partially encircles the tapering section 6 when the parts are in proper position. 25 When there are two brackets or platforms, as for instance, the two platforms 20, the brace 23 will practically encircle the tapering section 6 at that point and a complete platform is presented extending entirely 30 around the standard 4 as indicated in Figure 2.

In Figure 6, a slightly modified structure is shown wherein the tube 3, catch 10 and 35 associated parts are eliminated. In this form of the invention, the standard 4 is screwed into a socket 26 mounted on the base 27. The various brackets, fixtures and the like indicated in Figure 1 or others not 40 shown, may be mounted on the standard in a similar way to the way the brackets 19, 20 and 21 are mounted in Figure 1 but there will naturally be no vertical adjustment.

In Figures 7 and 8 a further modified 45 form of the invention is shown wherein the standard 28 is not only provided with apertures 29 and 30 similar to apertures 8 and 9 but with apertures 31 arranged beneath the shoulder 32, which shoulder is similar to shoulder 7. Also, the aperture 30 which 50 is at right angles to the aperture or passageway 29 is not in the same plane but is in the next tapering section of the standard. In 55 this form of the invention, the catch 33 is provided with a spring 34 whereby the catch extension 35 is resiliently held not only beneath the shoulder 32 but part extending into one of the apertures 31. The catch 33 is provided with arms 36 which are pivotally 60 mounted on the tube 3 but the pivotal mounting is below the catch extension 35 whereby the spring 34 is necessary to cause the extension to properly function.

65 In all the forms of the invention, means have been provided for receiving different kinds of fixtures whereby different kinds of

articles may be supported at the same time or at different times. In Figure 1, cage members have been shown at the upper part for receiving flower pots or other desired articles while below these members are arranged platforms or shelves which may receive either the same kind or different kinds of articles. It will, therefore, be observed that the device may be used by florists in displaying their goods or may be used in 70 stores of different kinds for displaying various articles desired to be displayed. Also, it will be evident that the stand may be used to display articles in a window, on a counter, or on the floor and one or many articles may 75 be supported for display without departing from the spirit of the invention.

What I claim is:

1. In a display rack, a standard formed with a plurality of shoulders and a plurality 85 of apertures, brackets provided with a projecting lug adapted to be received by an aperture, and a flange projecting from the bracket and adapted to engage a shoulder for holding the bracket against movement, 90

2. In a display rack, a standard formed with a plurality of spaced tapering sections, and a plurality of tubular sections, a tubular section merging into a tapering section, and a shoulder between each tapering section and each tubular section, the standard being provided with a plurality of spaced apertures, brackets removably mounted on said standards, each of said brackets being provided with a lug adapted to be received by an aperture and provided with a flange curved to conform to the curvature of a portion of the tapering section and having a free end engageable with the shoulder whereby the bracket will be held against movement, 105

3. In a display rack, a standard formed with a plurality of spaced tapering sections, a shoulder at the reduced end of each tapering section, said standard being provided with a plurality of apertures, a plurality of brackets removably mounted on said standard, each of the brackets having a lug received within an aperture, and a flange 110 projecting from the bracket adjacent each lug and curved to conform to the curvature of the tapering section and snugly embracing said section, 115

4. In a display rack, a standard formed with a plurality of spaced tapering sections, a shoulder at the reduced end of each tapering section, said standard being provided with a plurality of apertures located longitudinally along the standard and also circumferentially of the standard, a plurality of brackets removably mounted on said standard, each of the brackets having a lug received within an aperture and a flange from the bracket adjacent each lug and curved to conform to the curvature of the 125 130

tapering section, each of the curved flanges forming a segment of a circle so that a plurality of the brackets may be located in the same horizontal plane with the adjacent side edges of the flanges in coacting relation for aiding in maintaining the brackets against movement.

5. An adjustable display fixture comprising a base, a tubular member carried by the base, a standard slidably mounted in the tubular member, said standard being formed with annular shoulders, a pivotally mounted catch carried by the tubular member and adapted to engage a shoulder for maintaining the standard at a predetermined height, said standard being provided with a plurality of apertures, article receiving brackets removably mounted on the standard, said brackets having lugs received within the perforations, a flange projecting upwardly from the brackets and having its upper free end in engagement with a shoulder for aiding in maintaining the brackets against movement.

6. In a display rack, a standard formed 25 with a plurality of spaced tapering sections and a plurality of shoulders, each shoulder being located between a pair of the tapering sections, the standard being provided with a plurality of apertures arranged longitudinally, article supporting brackets having a lug seated within an aperture, and a flange connected with the bracket embracing the tapering section and having an edge engaging a shoulder so that the brackets will be 33 maintained against movement.

7. In a display rack, a standard provided with a plurality of apertures arranged longitudinally of said standard, brackets provided with a projecting lug adapted to be 40 received by an aperture, and a flange projecting from the bracket laterally from the lug and shaped to conform to a portion of the contour of the standard and adapted to snugly embrace the standard at such point 45 whereby the bracket is held against movement.

SELINA HAMBURGER.
